(57) **CLAIM**

I claim the ornamental design for a lighting device, as shown and described.

DESCRIPTION

FIG. 1 is a perspective view of a lighting device showing my new design, in an aligned configuration, as viewed from the top and one side.

FIG. 2 is a bottom plan view of the lighting device of FIG. 1 in the aligned configuration.

FIG. 3 is a top plan view of the lighting device of FIG. 1 in the aligned configuration.

FIG. 4 is a side elevation view of the lighting device of FIG. 1 in the aligned configuration, the other side elevation views being identical; and,

FIG. 5 is a perspective view of the lighting device of FIG. 1 in a tilted configuration, as viewed from the top and one side thereof.

The details shown in broken lines are for illustrative purposes only and form no part of the claimed design.
